UNITED STATES PATENT OFFICE.

W. H. BLACKMER AND E. R. CARPENTER, OF CLERMONT, IOWA.

IMPROVEMENT IN WATER-WHEELS.

Specification forming part of Letters Patent No. 58,208, dated September 25, 1866.

To all whom it may concern:

Be it known that we, W. H. BLACKMER and E. R. CARPENTER, of Clermont, in the county of Fayette and State of Iowa, have invented a new and Improved Water-Wheel; and we do hereby declare that the following is a full, clear, and exact description thereof, which will enable those skilled in the art to make and use the same, reference being had to the accompanying drawings, forming part of this specification, in which—

Figure 1 is a vertical section of our invention, taken in the line x x , Fig. 2; Fig. 2, a horizontal section of the same, taken in the line y y , Fig. 1.

Similar letters of reference indicate corresponding parts.

This invention relates to a new and improved horizontal water-wheel, of that class in which power is obtained by the direct and reacting force of the water, or by percussion and gravity.

A represents a pen-stock, in which the wheel is placed and works.

B is the wheel, placed on a vertical shaft, C, the lower end of which works on a point, a, in a bridge-tree, D, underneath the pen-stock. (See Fig. 1.)

The wheel B is composed of a circular head or block, b, having radial buckets c projecting from its periphery. The upper parts of these buckets have a vertical position, forming planes at right angles with the water as it comes in contact with them, and the lower parts are inclined and slightly curved, forming an angle of about forty-five degrees with the upper parts in a backward direction or at their rear, (See Fig. 1.)

The lower inclined parts of the buckets are about equal in height to the upper parts, and the former are encompassed by a band, d. The lower parts of the buckets, with the band d, are fitted in a circular opening, e, in the bottom of

the pen-stock, the upper edge of the band d and the upper edges of the lower parts of the buckets being flush with the upper surface of the bottom of the pen-stock.

The upper parts of the buckets are above the bottom of the pen-stock, and they are encompassed by three blocks, C' C' C', the inner surfaces of which are curved in such a manner as to form curved water-passages D D D, gradually decreasing in width from their outer to their inner ends, where they nearly touch the outer edges of the upper parts of the buckets. (See Fig. 2.) These water-passages are of equal dimensions and at equal distances apart, and are covered by a top-piece, E.

From the above description it will be seen that the water is let upon the wheel at three different points, and at first by impact upon or against the upper parts of the buckets, and then acts by gravity in passing down over the lower inclined parts of the buckets.

The width of the buckets are equal to the width of the orifices of the passages D, and the water, being confined to the wheel by the blocks C', acts upon or against the upper parts of the buckets with its percussive force, and at the verge of the wheel, while a free escape is allowed the water in passing down and over the lower inclined parts of the buckets, so as to obtain the most favorable effects from the force of power of gravity of the same.

Having thus described our invention, we claim as new and desire to secure by Letters Patent—

The combination of the radial buckets C C, the wheel B, blocks C' C' C', and water-passage D, all constructed and arranged in the manner and for the purpose herein specified.

W. H. BLACKMER.

E. R. CARPENTER.
